US00D939469S

(12) **United States Design Patent** (10) **Patent No.:** **US D939,469 S**
(45) **Date of Patent:** **** Dec. 28, 2021**

(54) **SPEAKER**

(71) Applicant: **BEIJING XIAOMI MOBILE SOFTWARE CO., LTD.**, Beijing (CN)

(72) Inventors: **Wei Yin**, Beijing (CN); **Yong Xu**, Beijing (CN); **Ningning Li**, Beijing (CN); **Zhiyao Wang**, Beijing (CN); **Tao Wang**, Beijing (CN)

(**) Term: **15 Years**

(21) Appl. No.: **35/510,486**

(22) Filed: **Jun. 22, 2020**

(80) **Hague Agreement Data**

Int. Filing Date: **Jun. 22, 2020**

Int. Reg. No.: **DM/210409**

Int. Reg. Date: **Jun. 22, 2020**

Int. Reg. Pub. Date: **Oct. 2, 2020**

(30) **Foreign Application Priority Data**

Primary Examiner — Mojtaba Tehrani

(57) **CLAIM**

The ornamental design for a speaker, as shown and described.

DESCRIPTION

The patent or application file contains at least one drawing executed in color. Copies of this patent or patent application publication with color drawing(s) will be provided by the Office upon request and payment of the necessary fee.

1.-2. Speaker

1.1 : Front

1.2 : Back

1.3 : Left

1.4 : Right

1.5 : Top

1.6 : Bottom

1.7 : Perspective view 1

1.8 : Perspective view 2

2.1 : Front

2.2 : Back

2.3 : Left

2.4 : Right

2.5 : Top

2.6 : Bottom

2.7 : Perspective view 1

2.8 : Perspective view 2

The product incorporating the designs is used for playing audio; the drawing designated to best show the essential features of the designs is the perspective view 1 of design 1; the design 1 is pointed as basic design.

1 Claim, 16 Drawing Sheets
(8 of 16 Drawing Sheet(s) Filed in Color)
